UNITED STATES PATENT OFFICE

EDWIN W. BEBIE, OF GRANTWOOD, NEW JERSEY, ASSIGNOR TO INTERNATIONAL PAPER COMPANY, OF NEW YORK, N. Y., A CORPORATION OF NEW YORK

EXTENSION CORE CAP

Application filed March 1, 1929. Serial No. 343,599.

This invention relates to core caps for the cores upon which paper produced in long sheets is wound into rolls for mounting in printing machines. Such cores are customarily made in tubular form of paper, straw-board, or similar material, and for the purpose of protecting the ends of the cores, and adapting them to withstand the weight and strain to which they are subjected when placed in the printing machine, it is customary to secure metal core caps to said ends. Such core caps are usually formed with means, as by the provision of a notch or cavity thereinto to engage a stud on a supporting chuck or spindle of the printing machine, connected to a friction wheel, by means of which the rotation of the roll is resisted, and the proper tension of the sheet secured as it is unwound and carried through the machine.

Such cores are made of different lengths according to the different widths of the paper sheets to be wound thereon, and in practice it has been found that after the core has been cut to a size which, after the caps are applied, will give an overall length to adapt the core for particular width of paper sheet, the core structure will shrink or shorten up, and will consequently no longer be suitable for having wound thereon, a paper sheet of such width.

It has been the practice in order to meet these conditions, to remove one of the caps, and cut off a portion of the core to reduce its length, and then replace the cap, so as to make the core suitable for receiving a paper sheet of lesser width than that of the sheet for which it was originally made; and these operations are repeated, when a further reduction in the length of the core occurs, until the core has been reduced in length to the minimum width of the sheets employed, after which the entire core must be discarded as unsuitable for further use.

This practice is attended with much loss of time in removing the core caps, cutting down the cores, and replacing the caps, and also with the loss of the cut-off material and the discarded cores, and entails correspondingly increased expense in the production and handling of the cores.

The present invention obviates this waste

of time and material and increased expense, by the provision of an extension core cap, which is adapted, in the event of the shrinkage of the capped core, to be applied to one or both of the main caps, so as to form an extension thereof, and thereby increase the overall length of the core structure, whereby the original length of the core structure may be restored, and the necessity for removing the main caps and cutting down the cores is avoided.

In the specification to follow, the invention will be described in detail, and the novel features thereof will be pointed out in the appended claims.

In the accompanying drawings:

Figure 1 is an elevation of a core provided with core caps, to one of which the improved extension core cap is applied;

Fig. 2 is a longitudinal section, on an enlarged scale, through one end of the same on the line 2-2 of Fig. 1;

Fig. 3 is an end elevation of the same; and

Fig. 4 is a perspective view of the extension core cap removed.

Referring to the drawings:

The core 1 is shown with core caps 2 applied to the ends thereof, to one of which core caps the improved extension core cap 3 is fitted.

The core 1 in the present instance is hollow, and the core caps 2 in the form shown by way of example to illustrate the application of my invention, comprise inner and outer annular flanges 2^a and 2^b, and an annular web 2^c connecting said flanges; and when said caps are applied to the ends of the core, the flanges will extend respectively at the inner and outer sides of the core at its ends, and the connecting webs will abut against the ends of the core as shown best in Fig. 2, where it will be seen that a portion of the inner flange of the cap is bent outwardly toward the outer flange to form a stud receiving notch or cavity 2^d, to adapt the core, with the roll of paper wound thereon, to be mounted and operated in the printing machine.

The above described core cap is but one example of the same, in connection with

which my invention may be employed, and it is obvious that other forms and varieties of core caps may be used, since my invention is not concerned with the main core cap, but has to do with an extension core cap to be fitted or applied to the main core cap, in order to make up for the shrinkage of the core structure after the main core caps have been applied.

10 For use in connection with the particular form of core cap shown, the improved extension core cap consists, as best shown in Figs. 2 and 4, of an outer flange 3^a, an inner flange 3^b of less depth, and a web 3^c connecting the outer ends of said flanges; and in applying the extension cap to the main cap of the core, the outer flange 3^a of the extension cap is tightly fitted over the outer flange 2^b of the main cap, and the inner flange 3^b 15 of the extension cap is abutted at its inner edge against the outer end of the main cap, and constitutes in effect a continuation of the inner surface of said main cap, the inner edge of the flange 3^b being in the present case, bent outwardly at intervals as at 3^d, so as to give the flange a more extended seat against the end of the main cap. A portion of the inner flange 3^b of the extension cap is bent outwardly toward the outer flange so as to 20 form a stud receiving cavity 3^e, which is preferably disposed in alignment with the stud receiving cavity 2^d of the main cap.

The extension cap may be firmly fastened to the main cap in various ways, as by a 35 driving fit of the outer flange of the extension cap over the outer flange of the main cap, or by indenting the material of the flange of the extension cap into the flange of the main cap, or in other ways, provided that 40 the extension cap will be fixedly held on the main cap and be prevented from circumferential movement relatively thereto.

In manufacturing the extension cap to meet the varying conditions as to the amount 45 of shrinkage of the core structure, the inner flange 3^b of the extension cap will be made of different depths, so as to obtain different increased overall lengths of the core structure, and so as to meet the varying and 50 changing degrees of shrinkage to which the cores are subjected.

In the practical use of capped cores, the shrinkage and reduction in length may take place during the period of time in which the 55 cores may be stored before having the paper sheet wound thereon, or it may take place after the paper has been wound thereon, and the core may be found after such shrinkage, to be considerably less in length than the 60 width of the paper sheet which the core was originally designed to accommodate. By the use of my improved extension cap, the original overall length of the core structure may be restored by fitting over one of the core 65 caps, an extension cap having an inner flange

of a depth corresponding to the amount of shrinkage, thereby adapting the core structure to receive a sheet of the width originally intended, and avoiding the necessity of thereafter cutting down the core to adapt the same for lesser width of sheets, since after the shrinkage has once taken place and the material of the core has once set, no further material reduction in length is apt to occur.

70 It will be apparent that by the use of the improved extension core cap, the loss of time in removing the main caps, cutting down of the cores, and the replacement of the caps, and the loss of material incident to the cutting down of the cores, will be entirely obviated, 75 and the capped cores may be employed for their full life without the necessity of finally discarding them when cut down to the minimum length, as has heretofore been done.

80 It will be understood that the detailed form of the extension cap may be variously changed and modified without departing from the limits of the invention, the particular form shown being that suitable for use in connection with the special form of main 85 core cap illustrated by way of example. The novel feature of the invention in its broader aspects, resides in the employment of an extension core cap adapted for application to the main core cap to increase the overall 90 length of the core structure, without regard to the specific form and detailed construction of the extension cap per se. It will be understood therefore that the invention is not limited to the exact form, construction, and 95 arrangement of the parts, except in so far as such limitations are specified in the claims.

100 Having thus described my invention, what I claim is:—

1. In combination with a hollow core for 105 paper rolls, a core cap applied to the end thereof to adapt the core for mounting and operation in a machine, and an extension annular core cap applied to the main cap to increase the overall length of the structure, said 110 extension core cap being formed with an inwardly extending portion seated against the outer end of the main cap.

115 2. In combination with a hollow core for paper rolls, a core cap applied to the end thereof, and an extension annular core cap applied to the main core cap to increase the overall length of the structure, said extension core cap being formed with an inwardly extending portion seated against the outer end of the main cap, said inwardly extending portion being provided with a stud receiving cavity at one side to adapt the lengthened core 120 for mounting and operation in a machine.

125 3. In combination with a core for paper rolls, a core cap applied to the end thereof and formed with a stud receiving cavity at one side to adapt the core for operation in a machine, and an extension core cap applied to the main cap to increase the overall length of 130

the structure, and formed at one side with a stud receiving cavity disposed in alinement with that in the main cap.

4. In combination with a hollow core for paper rolls, and a core cap applied to the end of said core and formed with flanges extending respectively at the inner and outer sides of the core, and having a connecting web extending across the end of the core, said cap being provided with a stud receiving cavity, an extension core cap applied to said core cap and provided with an outer flange surrounding and fixedly connected with the outer flange of the core cap, and provided also with an inner and shorter flange extending inwardly from the outer end of the outer flange and terminating at the outer end of the inner flange of the main core cap, said shorter flange constituting in effect a continuation of the inner flange of the main core cap, and said extension core cap being formed with a stud receiving cavity disposed in alinement with the cavity in the main cap.

5. In combination with a hollow core for paper rolls, an annular core cap applied to the end of the core to adapt the latter for mounting and operation in a machine, and an extension core cap comprising an outer flange surrounding the main cap, and an inner flange extending inwardly from the end of the outer flange and abutting against the outer end of the main cap and forming an extension of the inner wall of the same; whereby the overall length of the core structure is increased to the extent represented by the depth of said inner flange.

6. In combination with a hollow core for paper rolls, a core cap comprising inner and outer annular flanges receiving the end of the core between them, a portion of said inner flange being bent outwardly toward the outer flange to form a stud receiving cavity to adapt the core for operation in a machine, and an extension core cap comprising an outer flange surrounding the outer flange of the main cap, and a connected inner flange seated against the outer end of the main cap and having a portion bent outwardly to form a stud receiving cavity.

50 7. In combination with a hollow core for paper rolls, an annular core cap applied to the end thereof to adapt the core for mounting and operation in a machine, and an extension core cap applied to the main cap to increase the overall length of the structure, said extension cap comprising an outer flange surrounding the main cap, and an inner connected flange forming a continuation of the inner wall of the main cap, the inner edge of said inner flange being bent outwardly at intervals to seat against the outer end of the main cap.

8. An extension core cap adapted for application to the main core cap of hollow paper-roll cores to increase the overall length of the

core structure, said extension cap comprising an outer flange of a diameter to fit tightly around the main cap, and an inner connected flange to seat against the outer end of the main cap.

9. An extension core cap adapted for application to the main core cap of hollow paper-roll cores to increase the overall length of the core structure, said extension cap comprising an outer flange of a diameter to fit tightly around the main cap, and an inner shorter connected flange to seat against the outer end of the main cap.

10. An extension core cap adapted for application to the main core caps of hollow paper-roll cores to increase the overall length of the core structure, said extension cap comprising an outer flange of a diameter to fit tightly around the main cap, and an inner shorter connected flange to seat against the outer end of the main cap, a portion of said inner flange being bent outwardly at one side to form a stud receiving cavity.

In testimony whereof, this specification has been duly signed by:

EDWIN W. BEBIE.
